ROTARY PUMP WITH SLIDING PLATES.

1,385,619.

Specification of Letters Patent. Patented July 26, 1921.

Application filed May 10, 1920. Serial No. 380,381.

To all whom it may concern:

Be it known that I, EDMOND HENRY, residing at 19 Rue du Poteau, at Paris, Department of the Seine, France, have invented 5 certain new and useful Improvements in Rotary Pumps with Sliding Plates, for which I have filed application in France May 3, 1919, and of which the following is a specification.

10 This invention relates to improvements in rotary pumps with sliding plates, for the purpose of reducing the internal friction and resistance effects and of thereby increasing the mechanical efficiency, at the same time 15 affording a simplified construction which provides for an easy dismounting and assembling of the parts. These improvements are applicable to liquid pumps as well as to pumps employed for the compression of 20 gases or for producing a vacuum, and also to hydraulic motors containing any number of sliding plates.

The said improvements consist chiefly on the one hand, in the method employed to 25 regulate the movement of the sliding plates out of the grooves in the piston in which they are contained as well as the return movement of the plates into the said grooves, by means of two parallel ring-shaped members disposed one on each side of the rotating piston 30 and adapted to rotate freely by means of one of their edges which engages a bored out portion in the end of the main body of the pump concentric to the axis of the latter, the 35 said ring-shaped members having their other edge engaging the sliding plates by means of suitable cut out portions in the latter and if necessary through the medium of elastic means; and on the other hand in the method 40 of mounting the piston on its shaft in such manner as to provide for a slight longitudinal displacement of this latter under the action of lateral pressures, means being provided for properly limiting the sliding movement of the shaft. It is understood that 45 the hereinbefore mentioned arrangements can be employed in combination or independently, and all of these concur in the same end, viz, to diminish the internal friction 50 effects and resistances which are injurious to the mechanical efficiency, this result being obtained while at the same time providing as set forth hereunder a construction of a simple character and providing 55 for an easy dismounting and assembling on the spot.

In the present description, the invention is supposed to be applied to a pump having a piston mounted eccentrically with reference to the main body of the pump.

60 In the accompanying drawing which is given by way of example, Figure 1 represents a pump of this kind in vertical section perpendicular to its axis, Fig. 2 is a vertical section along the axis. Figs. 3 and 4 are 65 partial sections taken respectively perpendicular to and along the said axis and showing the method of disposing the elastic means between the ring-shaped members and the sliding plates.

70 The cylindrical body of the pump, *a*, which is closed by two covers *b*, *b'* forming end cover plates, contains the movable piston *c* which is also of cylindrical form but is mounted in eccentric position with reference 75 to the main body *a* in such manner that it shall be tangent at its lowest point to the interior surface of the said main body of the pump.

70 The tangency may take place according to a generatrix of the cylinder, or as represented in the drawing according to a surface of contact. In the latter case, the portion of the surface of contact which belongs to the pump body is not centered according to 80 the axis of the latter, but with reference to the axis of the piston, and the middle part of this surface portion is formed by an independent member *d* which is movable in a groove in the cylinder and is driven constantly against the piston by means of a 85 flat spring *e* in such manner that in spite of the wear of the parts, a good contact shall be always maintained and with a minimum amount of friction.

90 The sliding plates *f¹*, *f²*, *f³*, *f⁴* are disposed in the usual manner to slide by easy friction within corresponding radial grooves in the piston. On each side of the latter is disposed perpendicular to the shaft *j* a ring-shaped member *g* or *g'*, guided by means of its outer edge which moves within a circular recess *i* or *i'* bored in the corresponding end plate *b* or *b'* of the pump body and concentric with the axis of this body, while its 100 inner edge enters into suitable cut out portions *k¹* or *k²* of the sliding blades. The 105 said ring-shaped members can move freely in the recesses of the end plate and in the cut out portions of the sliding plates, but 110 they are drawn along by the sliding plates during the rotation of the piston while re-

maining nevertheless always concentric to the main body of the pump during their movement.

In order to provide for the entraining 5 of the said members with certainty, there are provided upon the ring shaped members on either side of the sliding plates or on either side of two oppositely situated sliding plates the studs $l-l'$, adapted to receive the 10 thrust of the corresponding sliding plate in case the entraining action has not taken place and consequently to give rise to this latter movement.

The part played by these ring-shaped 15 members is readily understood: under the action of centrifugal force, the sliding plates tend to bear upon the walls of the cylinder, and if they were free to move they would be projected against these walls, thus causing 20 a frictional effect which increases with the speed, and this will cause a considerable increase in the mechanical resistance. The ring-shaped members act to prevent this effect by limiting the outward movement of 25 the sliding plates to exactly the proper quantity in order that the plates shall run flush with the walls and provide the required tightness; by reason of their eccentric position with reference to the piston and 30 their concentric position relative to the cylinder, the ring-shaped members cause the sliding plates to enter into their grooves as soon as they arrive in the inoperative position during the revolution.

35 Moreover, since a partial vacuum is produced on the side of the intake, while a pressure exists on the delivery side, the sliding plates are thus subjected to efforts of a contrary nature, and on the intake side 40 these would tend to force the plate out of the piston, while on the delivery side they would tend to force the plate back into the piston, if the ring-shaped members did not maintain the plates in their respective positions.

The said ring-shaped members also have a veritable equilibrating action which still further tends to reduce the effect of centrifugal force, for in fact the mass of each 50 plate has opposed to it, as concerns centrifugal force, the mass of the assemblage formed by the other plates and the ring-shaped members connecting all the plates together.

55 In the pumps which operate at very high speeds, the elements can be designed so as to keep the plates somewhat within their grooves in order to prevent them from coming in contact with the walls of the cylinder, and this acts to suppress all friction.

For the plates which are employed to make a working joint, this very small setback of the plates will not prevent tightness, since this is assured by the extremely 65 high speed of the fluid; in the parts of the

pump in which the sliding plates are inoperative, this setback is of no importance.

The operation remains quite the same as for all pumps of this class. The intake is effected through the neck m , for instance, 70 and with the piston rotating in the counter-clockwise direction, if the piston is considered in the position indicated in Fig. 1, the plate f^1 is engaged upon intake, and this will prevail until the plate reaches the edge 75 n in the pump body; during this time the plate f^2 is engaged upon delivery in the direction of the neck m' , while the other two plates are inoperative during this period.

It is understood that a certain amount 80 of play is allowed where the ring-shaped members engage the cut out portions of the plates in order to provide for the displacement required by the fact that the angle between the plates and the ring-shaped members varies at each instant.

On the other hand it is advisable to provide proper arrangements whereby the plates are allowed a certain amount of radial displacement in order that they may 90 move toward the center of the cylinder, especially in cases where the pumps are employed for the intake and delivery of liquids which are subject to contain foreign bodies of a hard nature, for the purpose of 95 avoiding any damage due to the latter. To this end the cut out portions of the plates are enlarged and in each portion is disposed a flat spring, o or o' , between the plate and the corresponding ring-shaped member. 100 This spring bears simply by its free ends upon the periphery of the ring-shaped member and is slidable upon the latter, being fixed at its middle part upon one side of the cut out portion, as represented in Figs. 3 105 and 4.

The connection between the piston c and its shaft j is carried out by means of the long keys p , p' which provide for a longitudinal sliding movement of this shaft, this being limited on each side by the washers q , q' which are drawn along by the said keys during the rotation of the piston, the keys striking against these washers. In this manner any interior lateral pressures exerted upon the piston can be balanced, and should the shaft undergo a pressure upon one end, this pressure is not transmitted to the piston but is supported by the cylinder heads through the medium of the said thrust 110 washers, thus suppressing the increase in resistance which would be caused by the friction of the piston on the cylinder heads or end plates, and reducing the wear of the entire apparatus.

115 It is evident that the preceding arrangements will have the advantage of suppressing the friction effects which are injurious to mechanical efficiency and will provide a simple construction and at least a construc- 120 125 130

tion of a more simple nature than all others which have been hitherto employed for the same purpose. It is clearly shown in the drawings that it is a very easy matter to 5 dismount and to assemble the pump without being required to move the same. It suffices to remove one of the cylinder heads, whereupon the piston with its plates and ring-shaped members can be withdrawn; for 10 the assembling, these latter members will fall into place almost without effort. As indicated in Fig. 1, the sight holes r, r' with tight plugs can be provided around the cylinder for the purpose of inspecting the 15 pump without being obliged to remove the cylinder heads or end plates. These plugs can be provided with the necks s, s' for priming the pump.

Claims:

20 1. A rotary pump with sliding plates comprising, in combination, a cylindrical pump body having intake and delivery passages, a rotary piston with sliding plates and mounted eccentrically with reference to the 25 cylinder, two ring-shaped members freely rotatable by their outer edges within bored out recesses in the end plates of the pump body and concentric to the cylinder, and having their inner edges engaging grooves 30 provided in the sides of the sliding plates, which grooves are wider than the said edges and elastic means provided upon each sliding plate between the said plate and the 35 said ring-shaped member in order to allow the plate to enter within its groove in the

piston while passing over an accidental obstacle on the walls of the cylinder.

2. A rotary pump with sliding plates comprising, in combination, a cylindrical pump body having intake and delivery passages, a 40 rotary piston rotated by means of a shaft disposed eccentrically with reference to the cylinder, the said piston being slidable longitudinally with reference to the shaft between two lateral stop pieces, plates slidable 45 radially in the piston, and two ring-shaped members freely rotatable by their outer edges within bored out recesses in the end plates of the cylinder and concentric to the said cylinder, and having their inner edges 50 engaging lateral grooves in the said plates for the purpose of maintaining and guiding the latter.

3. In a device of the class described, the combination with a cylindrical body having 55 an inlet and outlet opening, a rotary piston eccentrically mounted with respect to the body, slots in said piston, slidable plates arranged in the slots, said plates having their inner ends of less width than their outer 60 ends, recesses in said inner ends, corresponding grooves in the walls of the body, rings limiting the movement of said blades movably mounted in said recesses and grooves, and spring means in said body for forming 65 a contacting surface at all times with the periphery of the piston.

In testimony whereof, I have signed my name to this specification.

EDMOND HENRY.
